US00D495716S1

(12) United States Design Patent (10) Patent No.: US D495,716 S
Sanschagrin et al. (45) Date of Patent:  Sep. 7, 2004

(54) ELEMENTS OF A COWLING

(75) Inventors: Stéphane Sanschagrin, St-Hyacinthe (CA); Pierre Vignau, Montreal (CA)

(73) Assignee: Bombardier Recreational Products Inc., Saint-Bruno (CA)

() Term: 14 Years

(21) Appl. No.: 29/193,238

(22) Filed: Nov. 7, 2003

Related U.S. Application Data

(62) Division of application No. 29/183,426, filed on Jun. 12, 2003, now Pat. No. Des. 486,157, which is a division of application No. 29/175,384, filed on Feb. 4, 2003, now Pat. No. Des. 484,144, which is a continuation of application No. 29/159,706, filed on Apr. 26, 2002, now Pat. No. Des. 474,784.

(57) CLAIM

The ornamental design for elements of a cowling, as shown and described.

DESCRIPTION

FIG. 1 is a perspective view of elements of a cowling showing our new design;

FIG. 2 is a rear view of the design of FIG. 1;

FIG. 3 is a left side view of the design of FIG. 1, the right side view being a mirror image; and,

FIG. 4 is a top view of the design of FIG. 1.

In FIGS. 1-4, broken lines showing environment or structure are for illustrative purposes only and form no part of the claimed design.

1 Claim, 3 Drawing Sheets
